UNITED STATES PATENT OFFICE.

LEWIS T. ADAMS, OF WHITMAN, MASSACHUSETTS.

EYELET-HOLE MACHINE.

SPECIFICATION forming part of Letters Patent No. 665,358, dated January 1, 1901.

Application filed October 30, 1896. Serial No. 610,528. (No model.)

To all whom it may concern:

Be it known that I, LEWIS T. ADAMS, of Whitman, in the county of Plymouth and State of Massachusetts, have invented certain 5 new and useful Improvements in Machines for Punching Holes in Boot and Shoe Uppers, of which the following is a specification.

This invention relates to machines for punching holes along the edge of the upper 10 of a boot or shoe for the insertion of eyelets.

The object of the invention is to provide a machine of this character which may be employed for punching eyelet-holes in uppers of different sizes and different styles in which 15 the holes should be differently spaced without removing and replacing any of the parts and merely by moving an operating-lever to one side or the other.

To this end the invention consists of a machine such as illustrated in the drawings and embodying those features of construction and arrangement which I shall now proceed to describe in detail and then point out in the claims hereto annexed.

Reference is to be had to the accompanying drawings, and to the characters marked thereon, forming a part of this specification, the same characters designating the same parts or features, as the case may be, wherever 30 they occur.

Of the drawings, Figure 1 is a plan view of a machine constructed in accordance with my invention. Fig. 2 is a front end elevation of the same. Fig. 3 is a vertical longitudinal 35 section on the line 3 3 of Fig. 1. Fig. 4 is a horizontal section on the line 4 4 of Fig. 3. Fig. 5 is a perspective view of one of the punching-blocks with a portion of the means for operating the punch. Fig. 6 is a longitudinal vertical section similar to that shown 40 in Fig. 3 and showing the punch as having passed through a layer of uppers. Fig. 7 is a horizontal view on the line 7 7 of Fig. 6. Fig. 8 is a partial sectional view on the line 45 8 8 of Fig. 3. Fig. 9 is a vertical sectional view on the line 9 9 of Fig. 6. Fig. 10 shows an upper with differently-spaced eyelet-holes punched therein by my machine.

In carrying out my invention I employ a frame having a base a and side standards a' , which are of the shape shown in Figs. 3 and 6 and which are connected at their upper

ends by a cross-plate a^2 , having a forwardly-projecting shelf a^3 and a vertical web a^4 . The standards are suitably braced by ribs a^5 . The 55 front edges of the standards are cut away, and the edges of the recesses are secured to a cross-brace b , between which and the shelf a^3 is placed a series of punch-blocks c . The rear ends of the punch-blocks lie between the 60 cross-plate a^2 and a cross-brace b' , supported by the standards a' , said plate and brace acting as guides therefor. Each punch-block is of the shape shown in Figs. 3, 5, and 6—that is to say, it is provided with two rearwardly-projecting fingers c' , through which a pivot-pin c^2 passes and extends into slots a^6 and b^2 in the said plate a^2 and cross-brace b' , respectively. The said slots are parallel longitudinally of the machine and guide the rear 65 ends of the punching-blocks in parallelism when the latter are moved and are adjusted, as will be hereinafter described, said pivot-pins sliding in the slots to allow the blocks to move longitudinally, and said blocks swinging laterally around said pins. 70

The front end of each punching-block is cut away or recessed, so as to provide a forwardly-projecting arm c^3 to receive the punch d and its holder d' , the latter passing loosely through 80 an aperture in said arm c^3 , as shown in Fig. 3, and an overhanging arm c^4 to receive an anvil e , against which the punch d is thrust by mechanism to be described.

On the shelf a^3 is secured a forwardly-projecting plate f by means of screws f' , it having a cam-slot f^2 , through which the anvil e in the punch-block loosely projects. 85

The slot f^2 is peculiar in shape, being curved somewhat similarly to the curved edge 90 of an upper, so that three of the anvils e are in a straight line, while the fourth one is removed from the line to quite a distance.

By removing the screws f' the plate f may be replaced by another one having a differently-shaped cam-slot, the shape of the slot corresponding to the predetermined line in which the holes are to be punched. 95

The holders d' for the punchers d are each tubular in form, with a flanged base d^2 , and they rest upon a vertically reciprocating cross-bar g , being held in place thereon by an angle strip or guide g' , so that they are free to slide longitudinally as well as transversely of 100

the said cross-bar g , while they are secured to it to reciprocate therewith.

- 5 Each punch is of the shape shown, having a shank d^3 , which fits in the enlarged opening in the upper end of the holder d' , with a flange d^4 resting on the top of the said holder, the upper portion of the punch being tapering in the usual way to provide a circular cutting edge.
- 10 The anvils each consist of a cylinder e , having a screw e' threaded into its upper end and bearing against some relatively soft material e^2 , placed within the tube and in which the punch may embed itself. Projecting forwardly from the arm c^3 of each of the punch-blocks is a pin c^5 , which enters one of a series of slots h' in a lever h , pivoted at h^2 to one of the standards, said lever having a handle h^3 , adapted to be held in any position 15 by a spring h^4 , secured to the other standard by screws $h^5 h^6$. The slots h' in the lever converge downwardly and are of unequal length, each slot increasing in length according to its distance from the pivot h^2 , so that when 20 the lever is operated the front ends of the punch-blocks are all brought nearer together in equal degrees. Now it will be seen that if the lever h is in its lowest position, as shown 25 in Fig. 2, and is raised to its highest position the punch-blocks will all be shifted nearer together, the anvils e in the slot f^2 serving to also shift the punch-blocks longitudinally as they are moved transversely or laterally by the said lever. The rear ends 30 have no transverse movements, as the rod or pin c^2 for each one acts as a pivot around which each is swung, the pin, however, sliding in the slots a^6 and the punch-blocks being thus guided longitudinally and transversely by the slots a^6 and f^2 , respectively. 35 In other words, the punch-blocks are moved or adjusted obliquely of the cross-bar g by the lever h acting in conjunction with the aforesaid slots. Hence by raising or lowering the lever I am enabled to adjust the 40 punches so that they may be employed for punching differently-spaced holes in uppers of different sizes and without removing any of the parts and substituting others therefor.
- 45 If desired, however, the lever h may be removed by removing screw h^3 and another one having differently-placed slots h' inserted in its place.

The cross-bar g is provided with two downwardly-projecting arms $g^{10} g^{10}$ to receive the ends $i' i'$ of a forked operating-lever i . The said front ends of the forked lever are pivoted to the arms g^{10} by a cross-pin g^2 , and the rear end of the lever i is connected by a bifurcated pitman-rod i^2 to a crank-pin i^3 on a crank-shaft i^4 , journaled in a bearing a^8 in the rear end of the machine. The said cross-shaft i^4 is provided with a suitable driving-wheel i^5 , with stop devices $i^6 i^7$.

60 In order to vary the throw of the punches, the lever i is fulcrumed on a vertically-adjustable pin or fulcrum j , the ends of which

are journaled in levers $k k$, pivoted to the standards a' by pivot-pins k' . A set-screw k^2 is threaded through the free end of a lever 70 k and bears against the base a , so that by driving the screw down farther through the levers k the latter may be raised, carrying with them the fulcrum j' , so as to vary the path of movement of the front end of the levers, as will be readily understood. The curved plate l , having a gage l' and a series of enlarged apertures l^2 , is secured to the standard between the arms $c^3 c^4$ of the punch-blocks in a position to support a pile of uppers for the punches as the latter are raised by the lever i . Preferably the apertures l^2 are sufficiently large to receive punches irrespective of the positions occupied by the latter, so that the same work-plate may be employed for uppers of various sizes in which holes differently spaced are punched.

65 From the foregoing it will be observed that I have provided an extremely simple machine by means of which I am enabled to punch eyelet-holes which are relatively near together or far apart, as occasioned by the size of the upper, the adjustment of the punch-blocks being effected by merely moving the handle h^3 of the lever h . The adjustment of the punch-blocks is not only lateral, but said blocks are adjusted so as to conform to the curved edge of any size of upper.

70 Referring to Fig. 10, I have shown an upper in which the holes on one side, as at 2, are spaced relatively far apart for a large-sized shoe, and on the other side, as at 3, are near together for a small shoe, both sets of holes being formed by my improved machine.

75 Having now particularly explained the nature of the invention and described a way of constructing and using the same, although without attempting to set forth all of the forms in which it may be made or all of the modes of its use, I declare that what I claim is—

1. A machine of the character described, comprising a frame, a set of punch-blocks, a punch mounted in each block, an anvil mounted in each block, means for operating said punches, and means for adjusting said punch-blocks simultaneously to adapt the punches for different sizes of uppers.

2. A machine of the character described, comprising a frame, a set of punch-blocks, a punch mounted in each block, an anvil mounted in each block, means for operating said punches, and a lever for adjusting said punch-blocks to adapt the punches and anvils for different sizes of uppers.

3. A machine of the character described, comprising a frame, a set of punch-blocks, a punch mounted in each block, a coacting anvil mounted in each block, means for operating said punches, means for guiding the punch-blocks, and a lever for adjusting said blocks to adapt the punches and anvils for different sizes of uppers.

4. A machine of the character described, comprising a frame, a set of punch-blocks, a punch mounted in each block, a coacting anvil mounted in each block, means for operating 5 said punches, means for guiding the punch-blocks transversely of the edge of the work, and a lever for moving all of said punch-blocks simultaneously toward or from each other. 10 5. A machine of the character described, comprising in its construction a frame, a series of punch-blocks each pivoted vertically in the frame, a punch in each block, an anvil in each block, means for operating the punches, 15 and a lever for swinging said blocks on their pivots so as to approach or recede from each other. 20 6. A machine of the character described, comprising in its construction a frame, a series of punch-blocks, each pivoted vertically in the frame, a punch in each block, an anvil in each block, means for operating the punches, and means for swinging said blocks toward or from each other on their pivots and means 25 for moving them bodily transversely of the edge of the work as they are swung toward or from each other. 7. A machine of the character described, comprising in its construction a frame, a series 30 of punch-blocks movably mounted in the frame, and means for adjusting said blocks, said blocks being each provided with a punch and an anvil. 8. A machine of the character described, 35 comprising in its construction a frame, a series of punch-blocks mounted in the frame, means for adjusting said blocks, an anvil set in each block, a punch in each block, and means for operating said punches simultaneously. 40 9. A machine of the character described, comprising in its construction, a frame, a series of punches each having a flanged base, a laterally stationary cross-bar on which said punches rest and having a flanged guide g' to receive said flanged bases of the punches, 45 means for adjusting said punches laterally, and means for raising and lowering said cross-bar. 10. A machine of the character described, 50 comprising in its construction, a frame, having horizontal guides, a series of punch-blocks held between said guides, a punch and an anvil mounted in each block, means for operating the punches, and means for adjusting the blocks simultaneously toward or from each other. 55 11. A machine of the character described, comprising in its construction, a frame, having horizontal guides, a series of blocks mounted 60 in said guides, each block having its front end recessed to constitute two forwardly-projecting arms, an anvil in the upper arm of each block, a punch in the lower arm of each set, and a work-plate arranged between the anvil and the punches. 65 12. A machine of the character described, comprising in its construction, a frame having horizontal guides, a series of punch-blocks each having a punch and its coacting anvil, and mounted between said guides, and each 70 having a pin on its front end, a vertical pivot for the rear end of each block sliding in longitudinal slots in the rear guides, one of the front guides having a transverse cam-slot for said pins on said blocks, and means for moving said blocks simultaneously. 75 13. In a machine of the character described, the combination of two independent sets of punch-levers, punches carried thereby, and a single operating device for simultaneously 80 moving the levers of both sets to adjust the punches toward and from each other. 14. A machine of the character described, comprising in its construction a frame, a series of punches, a support on which said 85 punches rest, means for adjusting said punches to vary their line of curvature and simultaneously therewith adjust them toward or from each other, and means for raising and lowering said support to operate the punches 90 simultaneously. 15. A machine of the character set forth comprising a frame, a set of punches, and means for adjusting said punches to vary their line of curvature and simultaneously 95 therewith adjust them toward or from each other, said means consisting of a rigid guide having a slot for securing said adjustment. 16. In a machine of the character described, the combination of punches, a guide having 100 a slot therein varying from an arc of a circle, and means for adjusting said punches in said slot to change their line of curvature. 17. In a machine of the character described, the combination with a plurality of punch-blocks each carrying a punch and an anvil, of means for adjusting said punch-blocks in 105 a line having a predetermined contour and simultaneously therewith adjusting them toward and from each other. 110 18. In a machine of the character described, the combination with a plurality of punches and a similar number of anvils, of means for simultaneously adjusting said punches and anvils in a sinuous line. 115

In testimony whereof I have signed my name to this specification, in the presence of two subscribing witnesses, this 20th day of October, A. D. 1896.

LEWIS T. ADAMS.
